DESIGN FOR A HANDBAG OR THE LIKE

Moe J. Cohen, New York, N. Y.

Application October 2, 1945, Serial No. 122,456

Term of patent 3½ years

(CL D87—3)

To all whom it may concern:

Be it known that I, Moe J. Cohen, a citizen of the United States of America, residing in New York city, county of New York, and State of New York, have invented a new, original, and ornamental Design for a Handbag or the like, of which the following is a specification, reference being had to the accompanying drawing, forming part thereof, wherein,

Figure 4 is a rear elevational view of the handbag or the like shown in Figures 1, 2, and 3.

I claim:

The ornamental design for a handbag or the like, substantially as shown.
